Primary Examiner — Darlington Ly*Assistant Examiner* — Jeremy Koenig(74) *Attorney, Agent, or Firm* — Renner, Otto, Boisselle & Sklar, LLP(57) **CLAIM**

The ornamental design for an axle plate, as shown and described.

DESCRIPTION

FIG. 1 is a top, front, left perspective view of an axle plate showing my new design;

FIG. 2 is a bottom, rear, right perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a bottom plan view thereof; and,

FIG. 8 is a top plan view thereof.

FIGS. 1-8 illustrate a left side axle plate, and the claimed design includes a right side axle plate that is a mirror image of the left side axle plate.

1 Claim, 4 Drawing Sheets(56)
